(57) CLAIM

The ornamental design for a container with sealed handle, as shown and described.

DESCRIPTION

FIG. 1 illustrates in perspective view an opaque container embodying the ornamental design of the present invention. A threaded neck portion is shown in phantom.

FIG. 2 illustrates in a first elevation view the container of FIG. 1 as viewed from its pinched handle. The threaded neck portion is shown in phantom.

FIG. 3 illustrates in a second elevation view the container of FIG. 1 as viewed from a side of its pinched handle. The threaded neck portion is shown in phantom.

FIG. 4 illustrates in a third elevation view the container of FIG. 1 as viewed from a side opposite its handle. The threaded neck portion is shown in phantom.

FIG. 5 illustrates in top plan view the container of FIG. 1. The threaded neck portion is shown in phantom.

FIG. 6 illustrates in second elevation view the container of FIG. 1 with a cap shown in phantom secured on the neck thereof; and,

FIG. 7 illustrates a perspective view of a translucent or transparent container showing a second embodiment of the ornamental design of the present invention.

The portions shown in phantom are for illustrative purposes only and form no part of the claimed invention.
